UNITED STATES PATENT OFFICE

EDWARD FRANCIS KRAMER, OF NEW IBERIA, LOUISIANA

PRESSURE-OPERATED SWITCH

Application filed January 5, 1928. Serial No. 244,684.

My present invention relates to automatic fire extinguishing systems of that type in which the fire to be extinguished is liable to occur in substantially closed rooms or compartments, where a blanket of gas containing little or no free oxygen may be automatically employed to smother say fire already kindled in such closed room or compartment.

10 Any suitable gas devoid of free oxygen may be used, but I prefer carbon dioxide as this is easily and cheaply prepared, and is highly efficient in use.

To secure the best results, this gas should 15 preferably be supplied by evaporation from holders containing liquid carbon dioxide. This gas not only will not support combustion, but also is not apt to injure the materials with which it comes in contact.

20 Such protection against fire may be provided in closed structures of many kinds, such as storage warehouses provided with individual store rooms, stores of various kinds, rooms used to store combustible materials, cellars, storage tanks for crude oil, or other substantially closed chambers or compartments containing goods liable to damage by fire.

I have shown the system as fitted to a 30 tank for storing crude oil, and arranged to extinguish fires occurring either under common conditions, or caused by lightning.

My invention will be more fully understood after reference to the accompanying 35 drawings, in which like parts are indicated by similar reference symbols throughout the several views, and in which

Figure 1 is a diagram showing in elevation, the complete apparatus as arranged to 40 extinguish the fire occurring in the crude oil tank.

Figure 2 is a sectional elevation showing the valve mechanism for controlling the flow of carbon dioxide gas from the container 45 holding the liquid, the valve being shown in the closed position and parts being shown in elevation.

Figure 3 is a similar view to Figure 2, but shows the upper end of the valve stem 50 in the lifted position.

Figure 4 is a diagram showing the thermostatically controlled circuit closing arrangement.

Figure 5 is a detail showing the holder for the magnetic bar used in closing the 55 circuit, and

Figure 6 is a diagram showing the circuit closing arrangement operated by lightning.

A represents the oil tank in which the fire is to be extinguished. In the oil tank shown, the level of the oil is at A', and the bottom of the tank is shown as broken away. This tank is fitted with the usual lightning rod B with conductor b grounded as at b'. C represents the container or holder for the liquid carbon dioxide which may be of any suitable size according to the requirements of the system; and obviously one or more of these containers may be used if desired. 60 65 70

Each of these containers is supplied with the usual reducing valve C', not shown, but these being of a well-known type will not be further described herein.

The carbon dioxide gas under pressure 75 flows through the pipe D to the inlet passage e in the valve casing E. This casing is provided with a valve seat E' below the chamber E''. This chamber E'' is connected by the passage E' to the pipe F, which terminates in the delivery pipe F' which is perforated as at f' in the chamber where the fire is to be extinguished. G represents the valve which is normally held firmly on its seat against the pressure of the carbon dioxide gas as will be hereinafter described. 80 85

This valve is connected to the valve stem G' having notches or pawl teeth g near the upper end thereof, in which the spring pawl H engages so as to hold the valve open after it has been lifted. The upper end of the valve stem is provided with the head G'' having an inclined slot g'', as shown in Figures 2 and 3, and in this slot the pin k carried by the lever K projects. This lever has a short arm K' connected by the pin k' to the links L, which links are connected to the pin e' carried by the valve casing. The long arm K'' of this lever carries the weight M which may be moved in or out on the 90 95 100

lever so as to hold the valve G on its seat with sufficient force. In order to lift the arm K² of the lever against the action of this weight, I provide a cable or chain N which winds on the drum P carried by the shaft Q' of the electric motor Q. This motor is driven by any suitable source of electric power such as a storage battery R. The normal position of the valve G would be closed as shown in Figure 2, and in order to operate the electric motor, the circuit to the same, which is normally open, must be closed.

This may be done by hand by swinging the switch S from the open position shown in Figure 1 to the closed position indicated in dotted lines in said figure. Such operation would normally be only for testing purposes. The automatic closure of the circuit through the electric motor may be effected either by the thermostatic arrangement shown in Figures 1, 4 and 5, or by shunt currents from a stroke of lightning, as shown in Figures 1 and 6. This automatic operation will now be described. Referring first to the thermostatic action occasioned by a rise in temperature as would occur when fire breaks out in the closed chamber, 1 and 1^a are two sealed containers filled with some gas whose pressure increases rapidly when subjected to small increases in temperature, for instance a suitable controlling medium I have found to be either liquid ammonia, or liquid sulphur dioxide. At a temperature of 100° F., liquid ammonia in a closed vessel would exert a pressure of about 213.6 lbs. per square inch absolute; and at a temperature of 115° F., the pressure would rise to about 269.2 lbs. absolute, thus giving an effective range for rise in temperature of 15° F. of 55 lb. to the square inch.

These containers 1 and 1^a are connected by the pipe 2 to the curved Bourdon tube 3, see Figures 1 and 4. In connection with this tube, I provide a dial 4 over which travels the pointer 5. This pointer is pivoted as at 6 and carries a pinion 7 meshing with the sector 8, which is carried by the long arm of the lever 9, which lever is pivoted as at 10 and is connected by the link 11 to the stud 12 of the Bourdon tube 3. As this tube expands, it will on the increase of pressure cause the pointer to travel around the dial in the clockwise direction. Connected to the stud 12 is the holder 13, having the jaws 14 loosely engaging the bar 15 of magnetic material such as steel or iron. This bar is secured to the L-shaped copper piece 16 pivoted at its end to the contact 17. The bar 15 is normally held in the jaws 14 by means of the weak spring 18, until the force of this spring is overcome by the magnet 19. This magnet is held at an adjustable distance from the bar 15 by means of the screw 20 and nut 21. When the bar is drawn to the

magnet, the arm 16^a will strike the jaw 22 of the contact piece 23 which is pivoted to the contact 24 connected to one of the wires of the circuit. It will be seen that when the pressure rises sufficiently in the Bourdon tube, the tube will be straightened out sufficiently to complete the circuit through the wires W and W', and this action will take place when the temperature in the top of the chamber A rises through a sufficient range.

The closing of the circuit through the wires W and W' will complete the circuit through the electric motor, and the motor will cause the drum P to wind up on the cable N and lift the valve G off its seat.

In order to prevent the continuous running of the motor, any suitable automatic cut out may be provided to cut the current off from the motor after the drum has rotated through a pre-determined number of revolutions.

Such automatic cut outs are well-known in the electrical art, and need not be further described herein.

The spring pawl H will hold the valve G lifted as long as desired.

In order to provide an audible signal in the circuit when closed, I include in said circuit an electric gong T, which is continually operated as long as the circuit is closed. The operation by a shunt current from a bolt of lightning will now be described.

The conductor 30 led from the lightning rod B passes around the electromagnet 31, see Figures 1 and 6, and this conductor is grounded as at 32, see Figure 1.

When lightning strikes the lightning rod, a considerable shunt circuit will flow through this conductor 30, and will energize the electromagnet 31 attracting iron bar 32, see Figure 6, which bar is pivoted as at 33 and has its upper end connected by the link 34 to the lever 35, which lever is normally drawn backward by the weak spring 36. This lever 35 carries a contact 37 connected to one of the wires W, and spaced apart from this is a similar contact 38 connected to one of the wires W'. When the electromagnet is energized, these two contacts 37 and 38 are brought together, and the circuit is closed, and the electric motor is put into operation.

In order to hold the contacts 37 and 38 in engagement after the shunt circuit has left the electromagnet, I provide a toggle arrangement 39 which will permit the lever 35 to be moved to the circuit closing position, but will retain it in such position when the toggle joint is straightened out. It will be seen that when a sufficient charge of electricity from the atmosphere strikes the lightning rod B, a shunt circuit will be created, which will put the electric motor 130

and the electric gong in operation, and will automatically lift the valve G and permit the flow of the carbon dioxide gas from the containers C to the closed chamber A.

Carbon dioxide being an inert gas is not likely to injure most of the articles found in stores, storage rooms, or other places where such protection against fire is specially needed, whereas the effect of water 10 sprinkler systems, when automatically operated, is often quite disastrous to the goods whose preservation is desired.

While the gas itself is not poisonous, it tends also to prevent the oxidation of the 15 blood in a person breathing too much of it; and to avoid accident to persons remaining too long in rooms filled with carbon dioxide gas, a small amount of naphthalene, ammonia, or other odor bearing volatile material 20 may be added to the carbon dioxide, so as to warn such persons to open doors or windows, and not remain in the closed compartment, after the fire has been extinguished therein, until proper ventilation has been 25 had.

While I have described liquid carbon dioxide as a specially suitable type of gas adapted to smother fires from cutting off the supply of free oxygen necessary to support 30 combustion, and liquid ammonia as specially adapted, from its rapid expansion under small changes in temperature, for operating the thermostatic circuit closer; obviously other suitable gases, either in the 35 liquid or gaseous states, may be substituted for the gases just mentioned.

While I have shown one embodiment of the invention in its preferred form, it will be obvious that various changes in the construction, combination and arrangement of 40 parts could be used without departing from the spirit of my invention; and I do not mean to limit the invention to such details except as particularly pointed out in the claims.

Having thus described my invention, what I claim and desire to secure by Letters Patent of the United States is:

1. A circuit closer comprising a Bourdon tube in communication with a source of 50 fluid under variable pressure, a holder movable with the tube and having jaws, an armature bar pivoted adjacent the tube and loosely received between said jaws, a light spring for retaining said bar against the 55 jaws, a magnet adjustably mounted opposite the armature bar, a movable contact carried by the bar, and a fixed cooperating contact positioned to be engaged by said movable contact.

60 2. A circuit closer comprising a movable switch actuating member, a holder movable with said member, an armature bar pivoted adjacent said member and received against said holder, a light spring for drawing the 65 bar against the holder, a movable contact

carried by said bar, a fixed contact positioned to be engaged by said movable contact, and magnetic means independent of said circuit situated out of magnetic influence with respect to the bar in the initial 70 position of the bar but within magnetic influence of the bar after the latter has been shifted on its initial movement by the movable switch actuating member for shifting the bar on its final movement to close the 75 contacts.

EDWARD FRANCIS KRAMER.
